(57) **CLAIM**

The ornamental design for a downrigger release and cable terminator, as shown and described.

DESCRIPTION

FIG. 1 is a perspective view of a downrigger release and

cable terminator of the present invention, the broken lines shown therein being for illustrative purposes only and forming no part of the claimed design;

FIG. 2 is an opposite side perspective view of the downrigger release and cable terminator, the broken lines shown therein being for illustrative purposes only and forming no part of the claimed design;

FIG. 3 is a top plan view of the downrigger release and cable terminator, the broken lines shown therein being for illustrative purposes only and forming no part of the claimed design;

FIG. 4 is a side elevational view of the downrigger release and cable terminator, the broken lines shown therein being for illustrative purposes only and forming no part of the claimed design;

FIG. 5 is a front elevational view of the downrigger release and cable terminator, the broken lines shown therein being for illustrative purposes only and forming no part of the claimed design;

FIG. 6 is an opposite side elevational view of the downrigger release and cable terminator, the broken lines shown therein being for illustrative purposes only and forming no part of the claimed design;

FIG. 7 is a bottom plan view of the downrigger release and cable terminator, the broken lines shown therein being for illustrative purposes only and forming no part of the claimed design; and,

FIG. 8 is a rear elevational view of the downrigger release and cable terminator, the broken lines shown therein being for illustrative purposes only and forming no part of the claimed design.
